H. G. VOIGHT,
DOOR STOP.
APPLICATION FILED APR. 20, 1917.

1,296,240.

Patented Mar. 4, 1919.

UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

DOOR-STOP.

1,296,240.

Specification of Letters Patent.

Patented Mar. 4, 1919.

Application filed April 20, 1917. Serial No. 163,409.

To all whom it may concern:

Be it known that I, HENRY G. VOIGHT, of New Britain, in the county of Hartford, State of Connecticut, have invented certain 5 new and useful Improvements in Door Stops, of which the following is a full, clear, and exact description.

This invention relates to door stops, and it has particular reference to devices of this 10 class which have means connecting the door with the door casing in such a manner that when the door is opened to a predetermined, but regulable degree, the opening movement will not only be arrested, but the door will 15 be held fixed in the open position.

One of the primary objects of the invention is to furnish a door stop of the general character indicated which is applicable, without adjustment, either to a right hand 20 door or a left hand door. My improved door stop is especially designed for association with a combined door check and closer, and as it is double acting so as to be applicable to doors of either hand, it may be 25 used with satisfaction on any preferred kind of double acting door check and closer, thereby imparting to the latter an added and very desirable function.

A further object of the invention is to 30 provide a very reliable, efficient door stop which can be readily and cheaply manufactured and assembled, and which is not liable to get out of order.

To these and other ends the invention con- 35 sists in the novel features and combinations of parts to be hereinafter described and claimed:

In the accompanying drawing,

Figure 1 is a fragmentary view of a door 40 having a door check and closer equipped with a door stop embodying my improvements,

Fig. 2 is an enlarged plan view of the swivel connection between the crank arm 45 of the door check and the link,

Fig. 3 is a section on line 3—3, Fig. 2,

Fig. 4 is an enlarged section on line 4—4

Fig. 1, with the door in the closed position,

Fig. 5 is a similar view, showing the po- 50 sition of the parts when the door is open,

Fig. 6 is an inverted plan view of the ear on the link,

Fig. 7 is a plan view of the ear on the crank arm; and

Fig. 8 comprises detail views of the ad- 55 justable abutment.

My invention is usually applied to a device comprising swiveled arms or members adapted to connect a swinging door with the door casing, and in some instances, it 60 may be embodied in the construction of a combined door check and closer, as in the example illustrated. In the form shown my improvements are applied to or associated with the swivel connection between the crank 65 arm of the door check and the link which carries the attaching foot or bracket. In the example shown the door check is mounted on the door, and the link is pivoted by means of the foot or bracket to the door 70 casing, and the link carries an adjustable abutment member or stop coöperating with a non-adjustable member on the pivot bolt; but it will be understood that various 75 changes and rearrangements of the device may be made without departing from the scope of the invention.

In the example shown the door 10 has mounted thereon a combined door check and closer 11, of well known type, having a crank arm 12, swiveled to a link 13 that carries a foot or bracket 14, applied to the door casing 15. These parts are all for the most part of the usual construction, and I have not considered it necessary to illustrate either the crank arm or the link in great detail, except for the swivel connection between the two, in which the present invention is embodied. The crank arm 12 has at 80 its outer end an enlargement or ear 16, and the link has a coöperating enlargement or ear 17, said ears being swiveled together by a bolt 18, and having between them a chamber 19, in which the stop mechanism is arranged. The bolt 18 is shown as being 85

of square cross section throughout a portion of its length, as shown at 20. It has a head 21, which is preferably counter-sunk in a recess at the under part of the ear 16; where- 90 as the square part 20 non-rotatively engages 95 100

a correspondingly shaped opening 22 in the ear, communicating with said recess. The square part 20 of the bolt extends into the chamber 19 and has fitted over the same a cam or eccentric 23. By tightening nuts 24, 25, engaging the threaded end of the bolt, the ears 16, 17 may be clamped together with the required degree of tightness to provide the swivel connection between the two arm members, and when the two ears are thus clamped together the eccentric or cam 23 is held in place between them in the chamber 19, and in non-rotative engagement with the bolt. The opposing edges or faces of the two ears are preferably provided with coöperating circular rabbets 16^a and 17^a, so that one will be effectively guided on the other, as shown at 26. Within the chamber 19 and coöperating with the relatively fixed cam 23 is an adjustable stop or abutment member 27. In the form shown this adjustable abutment partly embraces the cam 23, and is adapted to engage the side surface of the latter, said abutment being formed as a part of a ring. The part 27 may advantageously be semi-circular in shape, and its inner surface is formed to engage the side surface of the cam frictionally when the door is opened, as hereinafter described. The part 27 may be adjusted toward the cam by means of two adjusting screws 28, which are screwed laterally into the ear 17, which is provided with suitable sockets for said screws. The inner ends 28^a of the screws extend into notches 28^b in the outer part of the abutment 27, said notches being located on opposite sides respectively of the center of the abutment, and it will be seen, therefore, that by manipulation of the adjusting screws the adjustable abutment may be adjusted symmetrically with respect to the cam.

When the door is closed the narrow part of the cam is opposite the abutment as shown in Fig. 4, so that there is no engagement between these two parts. When, however, the door is opened, the wider part of the cam and the abutment are so displaced angularly with respect to the pivotal point of the two arms, that they engage each other, as shown in Fig. 5. This arrests the opening of the door at a point which is determined by the adjustment of the abutment 27, as will be understood, and when the coöperating surfaces of the cam and abutment move into engagement with each other the friction is sufficient to hold the door open against ordinary pressure, although the door can be readily closed when desired.

Owing to the eccentric shape of the part 23 the abutment 27 must obviously be free for a certain amount of lateral displacement relatively to the ends 28^a of the adjusting screws, and this is provided by suitable cutting of the notches 28^b. Fig. 5 shows

how the abutment is swung laterally to one side of the center of the bolt by the eccentric surface of the cam, and Figs. 4 and 5 in conjunction show how the notches 28^b are cut to permit this operation. The screws 28 permit the device to be very finely adjusted so that the door can be arrested and held in exactly the desired position. The device is applicable either to a right hand door or to a left hand door. In the case illustrated the abutment engages one side of the cam when the door is opened, but in the case of a door of opposite hand the abutment engages the opposite side of the cam in an obvious manner, so that no adjustment is required for conversion of the device from a right hand to a left hand stop, and vice versa.

If the cam and abutment become worn, they can be readily removed. To take the device apart it is merely necessary to remove the bolt 18, whereupon the ears can be separated and the cam and abutment removed. The cam is free just as soon as the bolt is removed, or can be readily slipped off of the bolt when the two ears are disengaged from each other. The parts are of comparatively simple construction, and as the coöperating stop members housed between the ears operate independently of the pivot bolt, with the ears retaining the same position longitudinally of said bolt at all times, the device is not liable to be readily damaged or to get out of order.

Various changes may be made in the details of the construction without departing from the scope of the invention as defined in the claims.

What I claim is:

1. In a door stop, a pair of arms, a bolt pivotally securing said arms together, said arms provided with a bearing to relieve said pivot bolt from transverse stresses, comprising an annular rib upon one arm and a coöperating annular groove upon the other arm, an eccentric cam mounted upon an intermediate portion of said bolt and non-rotatably connected by said bolt to one of said arms, and a non-yielding stop carried by the other arm and positioned to be engaged by said cam to limit the relative angular movement of said arms.

2. In a door stop, a pair of arms pivotally secured together, said arms provided with a bearing to relieve the connecting pivot from transverse stresses, comprising an annular rib upon one arm and a coöperating annular groove upon the other arm, an eccentric cam mounted between said arms upon said pivot and non-rotatably connected to one of said arms, and a non-yielding stop upon the other arm positioned to be engaged by said cam to limit the relative angular movement of said arms.

3. In a door stop, a pair of arms, a bolt

pivottally securing said arms together, said arms having an inclosed chamber formed therebetween, an eccentric ring mounted upon said pivot bolt within said chamber and non-rotatably connected to one of said arms by said bolt, and a non-yielding stop carried by the other arm within said cham-

ber and positioned to engage said eccentric ring to limit the relative angular movement of said arms.

In witness whereof I have hereunto set my hand on the 18th day of April, 1917.

HENRY G. VOIGHT.
